UNITED STATES PATENT OFFICE.

EDWARD M. HEWLETT AND THEODORE E. BUTTON, OF SCHENECTADY, NEW YORK, ASSIGNEES
TO GENERAL ELECTRIC COMPANY, A CORPORATION OF NEW YORK.

CIRCUIT-BREAKER.

No. 901,614.

Specification of Letters Patent.

Patented Oct. 20, 1902.

Application filed October 22, 1904. Serial No. 229,538.

To all whom it may concern:

Be it known that we, EDWARD M. HEWLETT and THEODORE E. BUTTON, citizens of the United States, residing at Schenectady, county of Schenectady, State of New York, have invented certain new and useful Improvements in Circuit-Breakers, of which the following is a specification.

The present invention relates generally to circuit-breakers but more particularly to that type of breaker in which one or more sets of shunt contacts are provided and in which the final break is made between carbon contacts.

The object of the invention is to improve circuit-breakers of this type generally and to that end it consists in certain structural features which will be best understood upon reference to the following detailed description taken in connection with the accompanying drawings, the novel features being definitely pointed out in the appended claims.

Referring to the drawings, Figure 1 is a front elevation of a circuit-breaker embodying the features of the invention; Figs. 2 and 3 are side elevations of the same, the former showing the breaker open, and the latter closed; Fig. 4 is a detail view illustrating the yielding connection between portions of the shunt contact supporting frame, the section being a complete section taken on a plane indicated by the line 4-4 of Fig. 7; Fig. 5 is a similar detail view, the section being taken on a plane corresponding to the line 5-5 of Fig. 7; Fig. 6 is a sectional view taken on the plane indicated by line 6-6 of Fig. 1; Fig. 7 is a partial sectional view taken on a plane indicated by line 7-7 of Fig. 4; Fig. 8 is a front elevation of the tripping coil and the lower contact stud and Fig. 9 is a perspective view of the shims and coacting parts by which the main bridging contact is adjusted.

Throughout these views like characters refer to like parts.

The breaker illustrated consists essentially of vertically-arranged contact studs A B mounted on a suitable support C, a trip magnet D comprising a yoke of iron E partially surrounding the lower stud, a main bridging contact F carried by a main supporting frame G pivoted at its lower end to the yoke E which constitutes a supporting base for the movable element of the breaker, an operating lever H, a main toggle I for cramping the bridging contact F into engagement

with the studs A and B, primary shunt contacts J K, secondary shunt contacts L M, a supporting frame N carrying the contact M, secondary toggles O for rocking the frame N to bring the shunt contacts L and M into engagement, and a cramping frame P for the toggles and operating parts pivotally connected at its inner end to the yoke E and at its outer end to the operating lever H.

The contact studs A and B are provided with the usual threaded shanks 10 and nuts 11 located in the rear of the support C, and said support which is composed of slate or other insulating material is provided with openings 12 by which it may be secured to the switchboard. The fixed shunt contacts J and L are electrically connected to the stud A, the former by direct connection and the latter through the bracket 13. The contact J consists merely of a removable plate held in position by bolts 14 while each of the contacts L is made up of a metal block 15 and a carbon block 16. These contacts L and M are supported by suitable holders 17 and 18, each of which consists essentially of two clamping plates 19 having engaging flanges 20 between which the carbon block 16 is firmly gripped by the clamping screw 21. The withdrawal of the carbon blocks from the holders in an upward direction by the action of the arc is prevented by pins 22 which engage recesses in the backs of the blocks as clearly illustrated in Fig. 6. When the carbon blocks are thus clamped, screws 23 are passed through the bracket 13 in the case of the holder 17, or the members 24 in the case of the holder 18, and through the lower end of the plates 19 into the metal blocks 15. With this construction it will be seen that in any case the metal block 15 may be readily replaced without removing the carbon block 16 from its holder; and on the other hand the carbon block may be withdrawn by merely loosening up the screws 21 and 23 without removing the block 15.

The lower contact stud B is surrounded on three sides by the magnetic yoke E which constitutes a support for the moving element of the breaker and which together with the stud B constitutes the trip magnet of the breaker. The armature 25 of this magnet is pivoted to a block 26 of brass or other non-magnetic material secured to the lower end of one arm of the yoke E and is adjusted so as to vary the air-gap by an adjusting screw 110

27 threaded within the lug 28 extending from the other arm of the yoke. The free end of the armature 25 is bifurcated for the passage of the lower end of the adjusting screw 27. This screw is provided with a head 29, which engages the under side of the armature, and a head 30 at its outer end which serves to indicate the calibration of the magnet upon the scale 31 carried by the 10 adjacent arm of the yoke. A jam-nut 32 is provided on the screw 27 and engages with the projection 28. For the purpose of obtaining a wide range of calibration with a relatively short scale plate, the armature 25 is provided with a weight 33 composed of non-magnetic material and disposed upon the armature so as to bring its greater mass toward the free end of the armature.

The bridging contact F is composed of a 20 bundle of laminations of phosphor bronze or equivalent material held between the plate 34 and the block 35 by a screw 36. This screw extends through the bundle of laminations and an intervening block 37 into a projection 38 on the block 35 which is seated within a recess in the block 37 as indicated by the dotted lines in Fig. 3. The block 35 is connected by a pivot 39 to the upper end of the main supporting frame G which in turn 30 is pivoted at its lower end to the lower end of the yoke E. There is a slight clearance between the block 35 and the adjacent part of the swinging frame G which permits a slight 35 rocking movement of the contact F so that it will satisfactorily seat itself upon the contacts A and B when pressed home by the operating lever H. The position of the contact F relative to its pivot 39 may be varied by means of U-shaped shims 40 inserted between the pivot block 35 and the block 37. These shims, which are shown in dotted lines in Fig. 3, and in Fig. 9 straddle the projection 38 on the block 35. By these shims, when the parts are assembled, the contact F may be adjusted so as to give the desired pressure between its ends and the studs A and B.

The operating lever H by which movement is transmitted to the various parts is journaled at its upper end upon a connecting pin 41 of the cramping frame P. This frame also comprises parallel links 42 which are connected at their outer ends to the pin 41 and at their inner ends to the upper part of the magnet frame E. The bridging contact F and its supporting frame G lie wholly within the cramping frame P, while the operating lever H straddles the cramping frame as clearly illustrated in Fig. 1. The bridging contact F is crimped into engaging 50 position by the main toggle I formed by the inward projection 43 on the operating lever H and the outward projections 44 on the frame G. As clearly illustrated, the parts are symmetrically disposed, the projection 43 lying between the projections 44 so that

strain imparted in forcing the contacts into engagement is taken up equally by the links 42. In closing the circuit-breaker, the operating lever H is moved downward and inward until the coöperating stops 45 45 upon the lever H and frame G respectively are brought into engagement. This occurs just before the main toggle I reaches dead center, so that the main toggle is never over-set and consequently as soon as lever H is free, the weight of the contact F and the frame G will open the breaker and cause the parts to assume the position illustrated in Fig. 2. To hold the circuit-breaker closed, a latch 46 is provided. This latch is pivoted at the point 47 to the frame G and engages a projection 48 on the operating lever H. The latch is tripped either manually or automatically, in the former case by pressing the button 49 and in the latter by the armature 25 of the 85 trip magnet engaging the under side of the rearwardly-extending arm 50 of the latch.

The secondary contact K is mounted at the upper end of a leaf-spring composed of one or more phosphor bronze strips which are carried by the main contact F and electrically connected with the lower stud B by means of the flexible strip 51, the lower end of said strip being secured to the under side of the stud B as clearly shown in Fig. 2. 95

The clamping plates 19 which constitute the holder of the shunt contact M are connected at their lower end to yieldingly-supported members 24 which are pivotally connected to the upper end of the frame N which in turn is pivoted at its lower end concentric with the main supporting frame G to the yoke E. Movement is transmitted to the frame N by means of the secondary toggles O each composed of the links 52 and 53 connecting said frame to the pivoted pin 41 on the cramping frame P. The connecting points between the links 52 and the frame N are so located that when the circuit-breaker is closed, they are in line with the pivots connecting the cramping frame P and the base C. Movement is transmitted to the secondary toggles O from the operating lever H by means of the shoulders 54 and 55 upon the sleeve 56 formed integral with the operating 10 lever H and the coöperating shoulders 57 and 58 on the links 53. Upon the downward movement of the lever H the shoulders 55 and 58 are brought into engagement and the toggles O are forced from the position of Fig. 120 2 to that of Fig. 3, the stops 59 on the links 53 engaging the projections 60 on the links 52 to arrest the toggles in the slightly over-set position. From this it will be seen that when the breaker is moved to open position, the main toggle I will first begin to move and the bridging contact F will have moved a considerable distance from the studs A and B before the shoulders 54 and 57 engage to break the secondary toggles O and allow the 130

circuit to be broken between the shunt contacts, L and M. During the movement of the parts prior to the breaking of the secondary toggles O the pressure between the shunt contacts L and M remains unchanged since any movement of the cramping frame P and the toggles O, occasioned by the movement of the operating lever H, will be about the common pivotal line extending through the pivot connecting said toggles to the frame N and the pivots connecting the frame P to the supporting base E previously referred to. The secondary circuit between the lower stud B and the shunt contacts M is completed by way of one or more flexible contact strips 61 which connect the upper side of the stud B with the base 62 on the frame N, as clearly illustrated in Fig. 2. The flexible strips 61 constitute a protective shield or apron to prevent the passage or falling of foreign substances into the space between the lower end of the contact F and the stud B, which would be difficult to dislodge and would cause damage to the breaker.

In order to electrically and yieldingly connect the frame N and the members 24, a coiled spring 63 and flexible strips 64 surrounding the spring are provided. These parts are inclosed in a spring case 65. The strips are connected at their opposite ends to the frame N and the members 24 by screws 66 and 67 as clearly illustrated in Fig. 4. The spring is a two-part coiled spring which is located within the spring case 65 and is firmly secured at its ends to the members 24, the spring bearing at its center through a suitable insulating block 68 against a central web 69 of that portion of the spring case connected to the frame N. This spring is coiled about the pivoted pin 70 and is suitably insulated therefrom by insulation 71 as clearly shown in Fig. 7. The spring 63 normally holds the contacts M in a position to cause a wiping engagement between them and the contacts L when the breaker is actuated, the contact points between the contacts moving from metal to carbon. By reason of the fact that this spring is insulated at 68 at its point of contact with the frame N it will not conduct current to the shunt contacts and will consequently not lose its temper. By means of the insulation 71 and the insulating washers 72, the frame N and the contact-carrying members 24 are substantially insulated from each other except through the flexible connection 64, so that practically all current conducted from one to the other must pass through this flexible connection. The movement of the members 24 relative to the frame N is limited by suitable abutting shoulders which are so located that when the circuit-breaker is closed the shoulders will abut as indicated by the dotted line 65 position of the members 24 in Fig. 4. This

produces a pressure between the contacts L and M which is caused by the toggles O and which is independent of the coiled spring 63 whose function is primarily to produce a wiping action between the contacts as they 70 separate.

In order to take up the jar resulting from the opening of the breaker, the upper end of the main supporting frame G is provided with a buffer which engages a stop 73 on the operating lever H. This buffer comprises a metal cap 74 mounted so as to move into and out of a socket 75 in the frame G. The cap is provided with a shank 76 which extends through the bottom of the socket and 80 is provided with a pin 77 which limits the outward movement of the cap 74. Beneath the cap and surrounding the shank 76 is a number of rubber washers 77^a which are of slightly smaller diameter than the socket 85 so as to leave a clearance around their outer edges. These washers act as a cushion and take up the force transmitted to the cap 74.

In operation the circuit-breaker is closed by the downward and inward movement of the operating lever H so as to bring the parts from the position illustrated in Fig. 2 to that illustrated in Fig. 1. On the other hand, in opening the breaker, the parts are moved in the opposite direction and in so 95 doing the main toggle first acts to withdraw the bridging contact F from engagement with the studs A and B. This is followed by the separation of the shunt contacts J and K and when both the contact F and 100 the shunt contact K have passed beyond arcing distance; the secondary toggle is actuated to break the circuit between the shunt contacts L and M. Until this point is reached, however, the pressure between 105 the shunt contacts L and M remains unchanged due to the unchanged position of the secondary toggle, and a good contact is maintained between the metal parts of said contacts. In the movement of the 110 contact M out of engaging position by reason of its spring connection with the spring case 65, the metal faces are gradually drawn out of engagement and the circuit is finally broken between the carbon contacts.

What we claim as new and desire to secure by Letters Patent of the United States, is—

1. In a circuit-breaker, the combination with a contact stud, of a magnet yoke in operative relation to said stud, an armature, a 120 scale, and means for indicating the adjustment of the armature upon the scale, said yoke, armature, scale and means being combined in a unitary structure.

2. In a circuit-breaker, the combination with a contact stud, of a magnet yoke in operative relation to said stud, an armature, a scale, and a screw for adjusting said armature, having a head indicating directly upon said scale the adjustment of said armature, 130

- said yoke, armature, scale and screw being combined in a unitary structure.
3. In a circuit-breaker, the combination with a contact stud, of a magnet yoke partially surrounding said stud, an armature adapted to complete the magnetic circuit about said stud, a scale, and means for adjusting said armature and indicating said adjustment upon said scale, said yoke, armature, scale and means being combined in a unitary structure.
4. In a circuit-breaker, the combination with a contact stud, of a flat magnet yoke, a scale, an armature movable in the plane of said yoke, and a screw for adjusting said armature lying in the plane of said yoke and armature and having a head for indicating directly upon said scale the adjustment of said armature.
5. In a circuit-breaker, the combination with a contact stud, of a magnetic conductor operatively related to said stud and constituting a supporting base, and a movable switch element carried by said base.
6. In a circuit-breaker, the combination with a contact stud, of a magnetizable yoke partially surrounding said stud and constituting a supporting base, a movable switch element carried by said base, means for latching said element in closed position, and means actuated by the magnet formed by said yoke and stud to trip said latching means.
7. In a circuit-breaker, the combination of vertically-arranged fixed contacts, coöperating movable contacts, and means for preventing the passage of foreign substances into the space between the lower contacts.
8. In a circuit-breaker, the combination of vertically-arranged fixed contacts, coöperating movable contacts mounted so as to rock about a point adjacent to the lower contacts, and a shield or apron for preventing the passage of foreign substances into the space between the contacts adjacent to said pivot.
9. In a circuit-breaker, the combination of a fixed element having vertically-arranged contact studs, a movable element having coöperating contacts, and an apron or shield connecting the fixed and movable elements so as to prevent the passage of foreign substances into the space between the lower contacts when the breaker is open.
10. In a circuit-breaker, the combination of a fixed element having vertically-arranged contact studs, a movable element having coöperating contacts, supporting and operating means for said movable element located adjacent to the lower stud, and a protective shield or apron lying above said means and below the upper stud.
11. In a circuit-breaker, the combination with vertically-arranged main and shunt contacts, a pivoted supporting frame for the movable shunt contacts, and a protective shield extending from the upper side of the lower fixed main contact to said frame.
12. In a circuit-breaker, the combination with vertically-arranged main contact studs and a brush for bridging said studs, of fixed and movable shunt contacts, a frame for supporting said movable shunt contact, and a broad, flexible conducting strip extending from the upper end of the lower stud to said frame so as to prevent the passage of foreign substances into the space between said lower stud and the adjacent end of the primary brush.
13. In a circuit-breaker, the combination with a support and fixed and movable switch elements, of a trip magnet carried by said fixed element, an armature therefor movable in a plane parallel to said support, and a latch for holding said movable element in closed position carried by said movable element and having an arm extending rearward in a direction substantially normal to the plane of said support into the path of movement of said armature.
14. In a circuit-breaker, the combination with a support and fixed and movable switch elements, of a latch carried by said movable element and adapted to hold said movable element in closed position, a trip magnet carried by said fixed element, and an armature movable in a plane parallel to said support and at right angles to the latch and operated by said magnet to trip said latch.
15. In a circuit-breaker, the combination with fixed contact studs, of a magnet yoke partially surrounding one of said studs, an armature pivoted to one arm of said yoke and adapted to complete the magnetic circuit about said stud, a movable switch element comprising a contact adapted to connect said studs, a latch for holding said movable element in closed position carried by said movable element and extending into the path of movement of said armature so as to be tripped thereby.
16. In a circuit-breaker, the combination with two pivotally-connected members, of means for limiting the movement of said members relative to each other, a coiled spring surrounding the pivot and connected with said members so as to yieldingly hold them in one limiting position, said spring being insulated from one of said members, and a conductor strip partially surrounding said spring and electrically connecting said members.
17. In a circuit-breaker, the combination with a supporting frame, of a contact-holder pivoted thereto, means for limiting the movement of said holder relative to said frame, a coiled spring surrounding the pivot and connected to said frame and holder so as to yieldingly hold said holder in one of its

- limiting positions, said spring being insulated from said frame, and a conductor strip partially surrounding said spring and connecting said frame and contact-holder.
5. 18. In a circuit-breaker, the combination with a supporting frame provided with a pivot, of a plurality of contact-holders mounted on said pivot, means for limiting the movement of said holders with reference to said frame, a coiled spring insulated from said frame and connecting said frame with said holders so as to yieldingly hold said contact-holders in one of their limiting positions, and conductor strips partially surrounding said spring and connecting said frame to said contact-holders.
10. 18. In a circuit-breaker, the combination with a fixed contact and a coöperating movable contact, of a supporting frame for said contact, a holder for said contact pivotally connected to said frame, a coiled spring surrounding said pivot and connecting said holder and frame so as to hold said movable contact in a position to produce a wiping engagement with the fixed contact when the supporting frame is moved to bring said contacts into engagement, means for insulating said spring, and a conductor strip partially surrounding said spring and electrically connecting said frame and contact-holder.
15. 19. In a circuit-breaker, the combination with fixed and movable main and shunt contacts, of a pivoted cramping frame, an operating lever journaled thereon, a toggle between each of said movable contacts and said lever, and means for operating said toggles in succession to break the circuit.
20. 20. In a circuit-breaker, the combination with fixed and movable main and shunt contacts, of a pivoted cramping frame, an operating lever journaled thereon, a toggle between each of said movable contacts and said lever, and means for operating said contacts, of a pivoted cramping frame, an operating lever journaled thereon, a toggle between each of said movable contacts and said lever, and operating means for said toggles whereby the position of the shunt toggle remains unchanged during the initial movement of the primary toggle in breaking the circuit.
25. 21. In a circuit-breaker, the combination with fixed and movable main and shunt contacts, of a pivoted cramping frame, an operating lever journaled thereon, a toggle between each of said movable contacts and said lever, and operating means for said toggles for said shunt contacts connected to the said supporting frame so as to remain concentrically movable with the cramping frame during the initial separation of the main contacts.
30. 22. In a circuit-breaker, the combination with fixed and movable main and shunt contacts, of independent toggles for operating the movable contacts, a pivoted cramping frame, and an operating lever common to both toggles supported on said cramping frame.
35. 23. In a circuit-breaker, the combination with fixed contacts, of coöperating main and shunt contacts both movable about the same center, independent toggles for operating the movable contacts, a pivoted cramping frame, and an operating lever common to both toggles supported on said cramping frame.
40. 24. In a circuit-breaker, the combination with fixed main and shunt contacts, a cramping frame, a main bridging contact movable
- within said frame, a main toggle working 65 within said frame to set and release said bridging contact, a movable shunt contact, and operating toggles therefor located outside of said cramping frame.
45. 25. In a circuit-breaker, the combination 70 with fixed main and shunt contacts, a pivoted cramping frame, a main bridging contact movable within said frame, a main toggle working within said frame to set and release said bridging contact, a movable shunt contact, an operating lever common to both main and shunt contacts, and a lost-motion connection with said lever whereby the shunt contacts are kept in engagement until the bridging contact has passed beyond arcing 80 distance.
50. 26. In a circuit-breaker, the combination with fixed main and shunt contacts, a cramping frame, a main bridging contact and its supporting frame movable within said cramping frame, a main toggle working within said cramping frame to set and release said bridging contact, a movable shunt contact, a supporting frame therefor straddling said cramping frame, operating toggles therefor located 90 without the cramping frame, and means comprising a common operating lever for successively operating said toggles.
55. 27. In a circuit-breaker, the combination with a fixed support and fixed and movable 95 main and shunt contacts, of means for setting and releasing the main contacts including a rocking cramping frame pivoted to said fixed support, a supporting frame for the movable shunt contacts, and operating toggles for said shunt contacts connected to the said supporting frame so as to remain concentrically movable with the cramping frame during the initial separation of the main contacts.
60. 28. In a circuit-breaker, the combination with fixed and movable main and shunt contacts and a base, of a cramping frame pivoted to said base, an operating lever journaled on said cramping frame, a main toggle for 100 moving the main contacts into and out of engagement, a supporting frame for the shunt contact, and secondary operating toggles for said shunt contact supporting frame connected at one end concentrically with the 110 connection between the operating lever and the cramping frame and connected at the other end to the supporting frame so as to make the movement of the toggles concentric with the cramping frame so long as the 115 toggles remain unbroken.
65. 29. In a circuit-breaker, the combination of fixed contacts, a pivotally-supported bridging contact, and one or more shims for adjusting the position of said bridging contact relative to its pivot.
70. 30. In a circuit-breaker, the combination with fixed and movable contacts, a pivoted

- supporting frame for said movable contact, an operating lever, a toggle between said lever and the movable contact for cramping said contact into engaging position, a latch 5 carried by said supporting frame, a lug near the end of said operating lever adapted to be engaged by said latch to hold the parts in cramping position, and means for tripping said latch.
- 10 31. In a circuit-breaker, the combination with fixed and movable contacts, a pivoted supporting frame for said movable contact, an operating lever, a toggle between said lever and the movable contact for cramping 15 said contact into engaging position, a latch carried by said supporting frame, a lug near the end of said operating lever adapted to be engaged by said latch to hold the parts in cramping position, and means mounted on 20 the base carrying the fixed contacts for tripping said latch.
32. In a circuit-breaker, the combination with a U-shaped magnet yoke, of an armature therefor pivoted at one end to one arm 25 of said yoke, a weight of non-magnetic material fixed to said armature, and means for adjusting the gap between said armature and yoke.
33. In a circuit-breaker, the combination 30 with a U-shaped magnet yoke, of an armature therefor pivoted at one end to one arm of said yoke, a weight of non-magnetic material fixed to said armature with its greater mass adjacent to the free end of said armature, and means for adjusting the gap between 35 said armature and yoke.
34. In a circuit-breaker, the combination with fixed and movable main contacts, of fixed and movable shunt contacts each comprising 40 metal and carbon contact blocks, clamping plates for clamping the carbon
- block, and means for removably securing the metal block and the clamping plates in position.
35. In a circuit-breaker, a contact holder 45 comprising a supporting plate, clamping plates bolted thereto, and means for drawing said plates toward each other to clamp the contact in position.
36. In a circuit-breaker, the combination 50 with a contact comprising metal and carbon blocks, of a holder for said contact comprising a supporting plate, clamping plates, means for removably securing said metal block and clamping plates to said supporting 55 plate, and means for drawing said clamping plates toward each other to clamp the carbon block in position.
37. In a circuit-breaker, the combination with a carbon contact block recessed on its 60 non-engaging side, clamping plates provided with projections extending into the recesses and also provided with flanges for engaging the edges of said block, and means for drawing said plates toward each other so as to 65 cause said flanges to grip said block to hold it in position.
38. In a circuit-breaker, the combination with a supporting frame, of a contact-holder pivoted thereto, a spring coiled about the 70 pivot and connecting said holder and frame, a flexible conductor connecting said holder and frame, and an inclosing case for said pivot, spring and conductor to protect the same against injury. 75
